UNITED STATES PATENT OFFICE.

DAVID H. WATTS, OF PHILADELPHIA, PENNSYLVANIA, ASSIGNOR TO HIMSELF AND WILLIAM C. SHARPLESS, OF SAME PLACE.

DESIGN FOR A TILE.

SPECIFICATION forming part of Design No. 16,668, dated April 27, 1886.

Application filed March 1, 1886. Serial No. 193,683. Term of patent 7 years.

To all whom it may concern:

Be it known that I, DAVID H. WATTS, a citizen of the United States, residing in Philadelphia, Pennsylvania, have invented a new and useful Design for a Tile, of which the following is a specification.

My design for a tile for decorative or other purposes is fully illustrated in the accompanying drawing, which shows in perspective view my new design.

The essential feature of my design is a flat tile having a plain surface, *e*, ornamented with undulating intersecting lines or grooves *b*, and having edges *a* of an undulating configuration corresponding with the undulations of the lines or grooves.

I claim—

The herein-described design for a tile of the flat character illustrated, and having a plain surface with undulating intersecting lines or grooves, and having its edges of a corresponding undulating configuration, substantially as shown and set forth.

In testimony whereof I have signed my name to this specification in the presence of two subscribing witnesses.

DAVID H. WATTS.
